Inventor

W. M. Hurlbert

UNITED STATES PATENT OFFICE.

W. M. HURLBERT, OF NORTHFIELD, VERMONT.

VARIABLE EXHAUST FOR STEAM-ENGINES.

Specification of Letters Patent No. 25,509, dated September 20, 1859.

To all whom it may concern:

Be it known that I, WILLIAM M. HURLBERT, of Northfield, in the county of Washington and State of Vermont, have invented a new and Improved Arrangement of Slides for Varying the Area of Opening of the Exhaust-Nozzles of Locomotives; and I do hereby declare that the following is a full, clear, and exact description of the same, reference being had to the accompanying drawings, forming part of this specification, in which—

Figure 1, exhibits a transverse vertical section of the smoke box of a locomotive with an outside view of the blast pipes. Fig. 2, is a section of the exhaust pipes and regulating slides in a plane parallel with Fig. 1. Fig. 3, is a horizontal section of the smoke-box, nozzles and regulating slides.

Similar letters of reference indicate corresponding parts in the several figures.

My invention consists in making the upper ends or nozzles of the blast pipes each in the form of an elbow or the inverted letter L, and fitting the regulating slides to the horizontal portions of the elbows substantially as herein described.

To enable others skilled in the art to make and use my invention I will proceed to describe its construction and operation.

A is the smoke box and B, B are the tubes of the boiler.

C, C, are the blast pipes arranged vertically side by side under the chimney H. D, D, are the elbow shaped nozzles fitted and secured to the mouth of the pipes and having openings a, a, in the top above the blast pipes. The horizontal portions of the elbows turn outward and are open, and have the slides E, E, inserted at their outer ends. These slides fit the horizontal por-

tions of the elbows, and may be of cylindrical, square or other form in their transverse section, but are represented cylindrical, and made hollow for the sake of 45 lightness. Their inner ends are closed and beveled on their under sides.

F, is a shaft fitted to rotate in bearings d, d, provided on the elbows D, D, but confined longitudinally and having upon it two 50 screw threads b, b, one right and the other left handed, said threads being fitted to corresponding female screws provided in lugs c, c, on the slides. The said shaft protrudes through the outside of the smoke 55 box where it is geared by a pair of bevel gears I, J, with a shaft G, which extends to the engineer's platform where it is furnished with a hand crank to turn it in either direction for the purpose of turning 60 the screw shaft F, and so adjusting the slides to cover or uncover a greater or less portion of the openings, a, a, and so regulate the exhaust, both sides being operated in a corresponding manner by the screw- 65 threads on the shaft F. This mode of applying the slides makes a very simple and effective arrangement for varying the area of the openings of the nozzles.

I do not confine myself to the means 70 herein described of operating the slides. But

What I claim as my invention and desire to secure by Letters Patent is—

Applying the slides to operate in elbows 75 or inverted L-shaped nozzles arranged substantially as herein described.

W. M. HURLBERT.
